TIMING APPARATUS FOR CLOCKS AND WATCHES

Thomas B. Gibbs, Delavan, Wis.

Application June 24, 1948, Serial No. 35,043

14 Claims. (Cl. 73—6)

1

The present invention relates in general to timing apparatus for clocks and watches, and more in particular to apparatus for timing and regulating the rate of the balance wheel of a clock or watch before it is assembled with the rest of the movement. It is the usual practice in the art to regulate the rate of a balance wheel by adjusting the length of the associated hairspring while the balance wheel is oscillating or vibrating and the operation is commonly referred to as hairspring vibrating.

Apparatus for hairspring vibrating as referred to in the foregoing is disclosed in the patent to Gibbs et al., No. 2,231,849, granted February 11, 1941. As disclosed in this patent, a balance wheel to be timed and regulated is temporarily supported in suitable bearings and is oscillated by hand, that is, it is started by hand and is allowed to oscillate freely at its natural frequency, the oscillations continuing long enough to permit the hairspring to be adjusted. Or the balance wheel may be restarted one or more time if necessary.

The invention is directed to an improved form of apparatus in which a balance wheel being timed is positively driven by impulses or puffs of air. The balance wheel is started by a strong air impulse, sufficiently powerful to initiate oscillation of the wheel at substantially full amplitude, and is then driven by so-called running impulses which are generated in response to oscillation of the wheel. These running impulses have a frequency which is one-half the beat frequency of the wheel, and drive the wheel while it is moving in one direction only, giving rise to a difficulty in coordinating the start of the running impulses with the motion of the wheel acquired in response to the starting impulse. The invention solves this problem and provides means for starting the wheel and for automatically starting the running impulses in phase with the wheel.

The invention will be described more in detail in the following specification, reference being had to the accompanying drawing, which shows diagrammatically the circuits and apparatus of a hairspring vibrating installation embodying the invention.

Referring to the drawing, the reference character 10 indicates a balance wheel having a hairspring 11, which is to be tested and adjusted. The balance wheel is supported on a suitable stand (not shown) having bearings for the balance wheel arbor so arranged that the wheel can be quickly placed in position and removed. The end of the hairspring is clamped between the 55 tron tube, and forms part of a stroboscopic indi-

2

two rollers 12 and 13, one of which is manually rotatable to feed the hairspring in and out to adjust its effective length. A stand such as described is well known and will require no further explanation.

10 The apparatus for generating and delivering air impulses to the wheels includes the supply pipe 15 which is connected to a suitable pump and reservoir system for supplying compressed air at constant pressure, with means for regulating the pressure to a value which is suitable for starting the wheels.

15 The strong starting impulses are generated by means of the valve 16, operated by the electromagnet 17, and are delivered to the wheels by the nozzle 18. The running impulses are generated by the valve 19, which is operated by the electromagnet 20. The running impulses are delivered by the nozzle 21 and are weaker than the starting impulses, due to the interposition of the reducing valve 22 in the branch supply pipe leading to valve 19. The reference character 23 indicates a surge tank.

20 A suitable source of light is indicated at 25, 25 while 26 indicates a lens or optical system arranged to project a light beam on to the rim of a balance wheel such as the wheel 10. The photo-cell 27 is so located that it intercepts the reflected beam and generates electrical voltages 30 responsive to the movement of the wheel, as explained in Patent No. 2,231,849, previously referred to.

35 The output of the photo-cell 27 is transmitted by way of the condenser 29 to an amplifier, represented by the rectangle 28, which may be of any known and suitable construction.

40 The tube 31 may be a type 6F6 pentode and has its control grid coupled to the amplifier 28 by means of the condenser 30 and the volume control potentiometer 32.

45 The reference character 33 indicates a transformer, the primary winding of which is included in the plate circuit of tube 31. The secondary windings of the transformer are connected in a direct current circuit which includes the full wave rectifier tube 34 and the load resistor 35. The tube 34 may be a 6x5G tube. A voltmeter 36 is provided to indicate the voltage developed across the resistor 35.

50 The tube 38 may be a type 884 Thyratron tube, connected as shown. It will be noted that the control grid of the tube is connected to the negative end of resistor 35, at junction 37.

The tube 43 is preferably a type 631P1 Stroboscop-

cator such as is disclosed in the patent to Gibbs, No. 2,361,281, granted October 24, 1944. This indicator includes a drum rotating at constant speed and provides a light spot which by its movement to the right or left indicates whether a balance wheel being tested is fast or slow.

The tubes 50 and 51 may be type 884 Thyratron tubes and are connected in a known circuit arrangement whereby they fire alternately in response to successive impulses received from tube 38 over conductor 44. The grids of the tubes have a fixed negative bias as indicated at 53 and the plates of the tubes are connected by the condenser 52.

The tube 60 may be a type 6N7 double triode and is wired according to a known circuit arrangement for operation as a delay device. It receives impulses through condenser 61 from tube 50 and transmits each impulse after a short time delay to the grid of tube 70 by way of condenser 63. The length of the delay can be adjusted by means of the potentiometer 64.

The tube 70 may be a type 2050 Thyratron tube and controls the circuit of the electro-magnet 28 associated with the air valve 19. The tube has a negative grid bias, as indicated at 71.

The operator is provided with a key K for controlling the apparatus. This key may be a telephone type key and has two positions, a normal or "stop" position, the position in which it is shown, and an operated position, or "start" position. The key is not self-restoring, that is, when operated it remains in operated position until restored by the operator.

The relay 72 is controlled by the key K and operates as a timing device to start the delivery of running impulses at the proper time with relation to the starting of a wheel to be tested, as will be explained presently.

The apparatus includes the necessary means for supplying current for operating the tubes and other equipment and the switches for turning the current on and off, as will be understood.

The operation of timing a balance wheel will now be described. For this purpose it may be assumed that the switches are closed, and that the compressed air apparatus is in operation, delivering compressed air under the proper pressure to the supply pipe 15.

When the current is turned on, the condenser 40 associated with the tube 38 charges in series with the plate resistor 41 and the voltage on the plate of the tube accordingly rises until the tube fires. The condenser 40 then discharges through the tube, causing the plate voltage to drop to such a low value that the tube is extinguished. The condenser 40 then charges again and the action is repeated. The values of resistance and capacity are such that the tube 38 fires at a frequency which is preferably about double the beat frequency of the balance wheels to be timed.

Each time the tube 38 fires, the potential on its cathode rises suddenly, due to the drop across the cathode resistor 39, and a positive impulse is transmitted by way of condenser 42 to the control grid of the Strobotron tube 43 of the indicator. These positive impulses control tube 43 in known manner. That is, the tube fires on each impulse and is extinguished quickly each time by the discharge of condenser 45. The flashes thus produced are seen by the operator as the spot of light previously referred to and show that the indicator is in working order.

The tube 38 also transmits impulses by way of conductor 44 and the condensers 54 and 55 to

the grids of tubes 50 and 51, which start firing alternately on successive impulses. The operation is well known and need not be explained in detail. Each time the tube 50 fires a positive impulse is transmitted to the delay device which includes the tube 60 and this device transmits delayed impulses to the grid of tube 70. The impulses have no effect, however, because the grid of tube 70 is grounded by way of contact 74 of the key K. The operation of the delay device will be explained more fully later on.

A balance wheel such as 10 may now be placed in position on the stand, with the free end of the hairspring clamped between the rollers 12 and 13. Having seen to it that the balance wheel is free to oscillate, the operator will operate the key K, moving it to start position, thereby closing contacts 75 and 76 and opening contact 74.

The condenser 77 has become charged through the resistor 78 and upon the closure of key contacts 76 the condenser discharges through the electro-magnet 17. The electro-magnet 17 accordingly energizes and opens the air valve 16, thereby delivering a strong starting air impulse to the balance wheel 10, which sets the wheel in motion in a clockwise direction. Although contact 76 remains closed, for the time being, the valve 16 is only momentarily operated, the electro-magnet 17 de-energizing following the discharge of condenser 77, because of the high resistance of resistor 78. The capacity of the condenser 77 is so related to the impedance of the electro-magnet 17 and the power required to operate the valve 16 that a very substantial and somewhat prolonged air impulse is given to the wheel, sufficient to start the wheel oscillating at approximately its normal amplitude.

The condenser 79 has also become charged, by way of resistor 80, and upon the closure of key contacts 75 the condenser discharges through the relay 72. Upon energizing, relay 72 closes its contact 73 and thus grounds the plate of tube 50, which extinguishes the tube if it should happen to be fired at the time relay 72 is energized. Relay 72 cannot remain operated in series with the resistance 80 and falls back after the condenser 79 has become substantially discharged. The capacity of condenser 79 is so related to the other characteristics of the circuit that relay 72 remains operated and keeps the plate of tube 50 grounded for about one full beat. The reason for this arrangement will appear later on.

The opening of key contact 74 removes ground from the grid of tube 70. The condenser 81 has become charged and the full B supply voltage is applied to the plate of the tube but the tube does not fire because of the negative bias on its grid.

When the balance wheel 10 is set in motion by the starting air impulse, certain variations are produced in the current which flows through the photo cell 27. The photo cell current is responsive to light reflected from the rim of the wheel and the variations are due to movement of the wheel beneath the impinging light beam. Thus, current variations are produced while the wheel is in motion, which cease when the wheel stops to reverse its direction of movement.

The photo cell currents are amplified by the amplifier 28 in known manner and a varying voltage is developed across the winding of the potentiometer 32. This voltage, or a selected portion thereof, is delivered to the grid of the tube 31 and causes variations in the current in the 70 plate circuit of the tube, said circuit including

the primary winding of the transformer 33. Voltages are thereby induced in the secondary winding of the transformer, which cooperates with the rectifier tube 34 to produce a flow of direct current in a circuit which includes the load resistor 35. The direction of current flow is such that the potential at junction 37 is negative with respect to ground. The voltage is indicated on the voltmeter 36 and may be adjusted to the proper value for satisfactory operation by means of the potentiometer 32.

The starting impulse causes the wheel 10 to make one half beat in a clockwise direction, or at least approximately one half beat. During this movement of the wheel a negative potential is produced at junction 37 in the manner described, and since the junction 37 is connected to the grid of tube 38, the negative potential prevents the tube from firing. The interval of one half beat during which tube 38 is thus held under control is long enough to enable condenser 40 to become charged, in case tube 38 should have fired just before the wheel was started.

When the wheel stops to reverse its direction of movement, the generation of varying photo cell currents ceases and the potential at junction 37 falls to zero. The negative potential at the grid of tube 38 being thus removed, the tube fires in the manner previously described and transmits a positive impulse over conductor 44 to the grids of tubes 50 and 51. Tube 50 is inoperative at this time due to its plate having been grounded by relay 72. Tube 51 fires responsive to the impulse received over conductor 44.

The wheel now makes one full beat in a counterclockwise direction. Throughout this beat the movement of the wheel produces a negative potential at junction 37 and at the grid of tube 38, which prevents the tube from firing.

At some point during this counter-clockwise beat, preferably about midway during the beat, relay 72 de-energizes and removes ground from the plate of tube 50, thus preparing the tube for firing on the next impulse from tube 38.

At the end of the counter-clockwise beat the wheel stops again, the potential at junction 37 falls to zero, and the tube 38 fires again, thereby transmitting another impulse over conductor 44 to the grids of tubes 50 and 51, which now causes tube 50 to fire. When tube 50 fires, the plate potential drops sharply, whereby a negative impulse is transmitted by way of condenser 52 to the plate of tube 51 and the latter tube is extinguished. Tubes 50 and 51 continue to fire alternately responsive to successive impulses from tube 38, now firing at beat frequency under control of the wheel.

The wheel now makes a full beat in a clockwise direction, the direction in which it is rotated by the starting impulse. About the middle of this beat it is given a running impulse of air by opening valve 19, which is responsive to the firing of tube 38 at the end of the first counter-clockwise beat as will now be explained.

When tube 38 fires it causes tube 50 to fire, as already described. When tube 50 fires, the potential on its cathode rises suddenly, due to the drop across the cathode resistor, and a positive impulse is transmitted to grid B of tube 60 by way of the condenser 61.

The two sections of tube 60 are referred to herein as sections A and B respectively, and the grid and plate elements likewise. Section A is normally passing current, grid A being connected to the cathode. Grid B is connected to ground

and the positive potential on the cathode due to current flow in section A produces a negative bias on grid B, which prevents section B from passing current. This is a stable condition, in which condenser 65 becomes charged to substantially the potential of the -B lead.

When the positive impulse is received at grid B from tube 50, section B starts to pass current and the potential on plate B drops suddenly, driving grid A negative due to the charged condition of condenser 65. The fall of potential at grid A decreases the current flow in section A, which causes the potential at plate A to rise. The rise of potential at plate A raises the potential on grid B, due to the coupling through condenser 62, which increases the current flow in section B and causes a further drop in potential at plate B. Thus, a kind of regenerative action takes place whereby the voltage at plate B falls very quickly to a low value and the grid A attains a negative potential which biases section A to cut-off.

The condenser 65 now starts to discharge through section B of the tube and the potential on grid A gradually rises toward the cathode potential. When the grid potential reaches a high enough value so section A can begin to pass current, the regenerative action is repeated and the tube returns quickly to its original condition, in which section A is conductive and the grid of section B is biased to cut-off.

The cessation of current flow in section B of tube 60 produces a sudden rise in potential at plate B, thereby transmitting a positive impulse through condenser 63 to the control grid of the Thyratron tube 70, causing this tube to fire. The firing of tube 70 causes the condenser 81 to discharge in series with the tube and the winding of the electro-magnet 20. This gives a short powerful energization of the electro-magnet and at the same time extinguishes tube 70, owing to the high resistance of resistor 82. The condenser 81 charges up again through the resistor.

The energization of the electro-magnet 20 opens the air valve 19 momentarily, thereby delivering an impulse of air to the wheel 10. This is the running impulse just referred to, which is given to the wheel at about the middle of the first full beat in a clockwise direction. The air impulse is responsive to the firing of tubes 38 and 50 at the end of the first counter-clockwise beat, but sufficient delay is introduced at tube 60 so that the air impulse is delivered to the wheel at about the middle of the succeeding clockwise beat, as stated. The amount of delay required depends on the operating time of the electro-magnetic valve mechanism 19-20 and can be adjusted to the proper value by means of the potentiometer 64.

At the end of the beat the tube 38 fires again, firing tube 51 and extinguishing tube 50.

The wheel now makes the second counter-clockwise beat. At the end of the beat tube 38 fires again, firing tube 50 and extinguishing tube 51. Tube 50 transmits an impulse to the delay device 60 which in turn transmits an impulse to the Thyratron tube 70 at the proper time to energize electro-magnet 20 again and give the wheel another running impulse during the next clockwise beat. The operation continues in this manner, the wheel running free during each counter-clockwise beat and receiving a running impulse during each clockwise beat. The running impulses should have the right amount of power to maintain the oscillation of the wheel at the proper

amplitude and can be adjusted as to power by means of the reducing valve 22.

When the oscillating balance wheel takes over control of the tube 38, the impulses which this tube transmits to the Strobotron tube 43 of the indicator are transmitted at the beat frequency of the wheel and by watching the indicator the operator is able to tell whether the wheel is fast or slow. In practice the hairsprings are always made too long, so the wheel will be slow. The operator accordingly shortens the effective length of the hairspring by rotating the roller 13, and cuts off the spring when the adjustment is correct as shown by the indicator. This regulating operation is well known and will require no further explanation.

The key K is restored as soon as the wheel has been timed and regulated. The restoration of the key grounds the grid of tube 70, which stops the operation of the running air valve 19. The restoration of the key also disconnects the magnet 17 and relay 12 from the condensers 71 and 79, respectively, and permits these condensers to charge preparatory to the starting of another wheel.

The wheel which has just been regulated may now be removed and replaced by another wheel to be timed and regulated, whereupon the key K is again moved to its start position and the operations described are repeated.

The invention provides an arrangement for starting the balance wheels which is very reliable and which saves time by starting the wheels off at substantially full amplitude. The operator's work is simplified, moreover, since the control key has only two positions and the starting of the running impulses is accomplished automatically at the proper time after the key has been moved to start position and the initial starting impulse has been given to the wheel.

The invention having been described, that which is believed to be new and for which the protection of Letters Patent is desired, will be pointed out in the appended claims.

I claim:

1. Apparatus for regulating the rate of a balance wheel and hairspring, comprising means for supporting a wheel for oscillation, means including a manually operated switch for delivering a starting impulse of air to said wheel to start the same, means responsive to oscillation of said wheel for generating an electrical impulse each time the wheel stops to change its direction, means for generating running air impulses responsive to the odd electrical impulses, means including a timing device started by operation of said switch for preventing generation of a running air impulse responsive to the first of said electrical impulses, and means for comparing the frequency of said electrical impulses with a standard frequency.

2. Apparatus as claimed in claim 1, wherein the timing device comprises a condenser which is charged while said switch is in normal position, and a relay energized by discharge of said condenser when said switch is operated.

3. In an apparatus for regulating the rate of a balance wheel and hairspring, means for supporting a wheel for oscillation, means including a manually operated switch for delivering a starting impulse of air to said wheel to start the same, said means also including electromagnetic air impulse generating mechanism and a circuit for said mechanism closed by operation of said switch, means responsive to oscillation of said

wheel for delivering running air impulses to said wheel, and timing means responsive to the operation of said switch for starting the delivery of said running impulses in phase with the wheel.

4. Apparatus as claimed in claim 3, wherein the timing means includes a condenser, and a relay, the energization of which depends on the charge in said condenser.

5. In an apparatus for regulating the rate of a balance wheel and hairspring, means for supporting a wheel for oscillation, means including a manually operated switch for delivering a starting impulse of air to said wheel to start the same, means responsive to oscillation of said wheel for delivering running air impulses to said wheel, means comprising a timing device started by said switch for automatically measuring a time interval beginning with the starting of said wheel, and means controlling said running air impulse means and operable in response to said timing device to delay the start of said running impulses until said time interval has expired.

6. In an apparatus for regulating the rate of a balance wheel and hairspring, means for supporting a wheel for oscillation, a manually operable switch having start and stop positions, means responsive to movement of said switch to start position for delivering an impulse of air to said wheel to start the same, means responsive to oscillation of said wheel for delivering running air impulses to said wheel, and means operating automatically while said switch remains in start position for causing said running impulses to be started in phase with the wheel, said last means including a device for preventing the delivery of the first running impulse until the wheel resumes its motion in the same direction as the direction in which it was started.

7. In an apparatus for timing a balance wheel and hairspring, means for supporting a balance wheel for oscillation, two nozzles for delivering air impulses to said wheel, an operator's switch, means responsive to the actuation of said switch for delivering a strong starting impulse to said wheel through one nozzle, including means for preventing the delivery of more than a single starting impulse responsive to such actuation, and means responsive to the oscillation of said wheel while said switch remains in actuated position for delivering relatively weak impulses to said wheel through the other nozzle.

8. In an apparatus for timing a balance wheel and hairspring, means for supporting a wheel for oscillation, pneumatic mechanism for delivering air impulses to said wheel, an operator's key, electromagnetic means responsive to actuation of said key to operate said mechanism to deliver a strong impulse of air to said wheel to start the same, means responsive to the oscillation of said wheel to generate an electrical impulse at the end of each beat, means responsive to alternate electrical impulses to operate said mechanism to generate light running air impulses to drive said wheel, said running impulses having a frequency equal to one half the beat frequency, means responsive to the said actuation of said key to insure that the first running impulse is generated responsive to the second electrical impulse and at a time when the wheel is moving in the same direction it moves in response to the starting impulse, and means operative to introduce a time interval between each electrical impulse and the running impulse responsive thereto, said intervals being of the proper duration to cause the running impulses to be delivered to the wheel in

such timed relation to its motion that the wheel is efficiently accelerated by each running impulse.

9. In an apparatus for timing a balance wheel and hairspring, means for supporting a balance wheel for oscillation, mechanism for applying air impulses to said wheel, an operator's key, means responsive to actuation of said key to operate said mechanism to start said wheel, means responsive to oscillation of said wheel for generating a series of electrical impulses of beat frequency, means responsive to alternate impulses of said series for operating said mechanism, a relay and circuit controlled thereby for controlling the response of said last means to said impulses, and means also responsive to the actuation of said key to produce an operation of said relay to control said circuit and cause said impulse responsive means to start its response with the second impulse of said series.

10. In an apparatus for timing a balance wheel and hairspring, means for supporting a balance wheel for oscillation, mechanism for applying air impulses to said wheel, an operator's key, means responsive to actuation of said key to operate said mechanism to start said wheel, means responsive to oscillation of said wheel to generate a series of electrical impulses of beat frequency, a pair of space discharge devices arranged to fire alternately responsive to impulses of said series, means responsive to each firing of the first one of said devices to operate said mechanism, a relay and a circuit controlled thereby effective to render the first said device incapable of firing, and means responsive to the said actuation of said key to produce a momentary operation of said relay extending from a time prior to the generation of the first impulse of said series to a time between the generation of the first and second impulses of said series, whereby the first said device is prevented from firing on the said first impulse of said series.

11. In an apparatus for timing a balance wheel and hairspring, means for supporting a balance wheel for oscillation, mechanism for applying air impulses to said wheel, means responsive to oscillation of said wheel for operating said mechanism, said last means including a space discharge device, an operator's key, a circuit including contacts of said key and effective to render said device inoperative when said key is in normal position, and means responsive to actuation of said key for operating said mechanism to start said wheel, said circuit being effective upon restoration of said key to stop said wheel.

12. In an apparatus for timing a balance wheel and hairspring, the combination of, a support adapted to mount a balance wheel for oscillation about its axis, a valve adapted when opened to deliver to a wheel on said support a starting impulse of gas under pressure of a predetermined magnitude sufficient to overcome the inertia of the wheel when the hairspring thereof is

deenergized and to oscillate the wheel substantially through its full range from a position of rest, a manually operated switch, means operable in response to actuation of said switch to open said valve long enough for delivery of said starting impulse and then close the valve, a second valve adapted when opened to deliver to said wheel a running impulse of gas under pressure of a magnitude less than said predetermined magnitude, and means operable after the delivery of said starting impulse and in timed relation with oscillations of said wheel to open said second valve periodically for the delivery of a succession of said running impulses in phase with the wheel.

13. In an apparatus for timing a balance wheel and hairspring, the combination of, means adapted to support a balance wheel for oscillation about its axis, mechanism adapted when activated to deliver an impulse of gas under pressure against a wheel on said supporting means for turning the wheel about its axis, a manually operated switch, means operable in response to actuation of said switch to activate said mechanism for delivering to said wheel a single starting impulse of predetermined magnitude sufficient to overcome the inertia of the wheel and oscillate the latter substantially through its full range from a position of rest, and means operable in response to oscillations of said wheel and after delivery of said starting impulse to activate said mechanism for delivering to the wheel a succession of running impulses in phase with the oscillations thereof and of substantially constant magnitude less than said predetermined starting impulse magnitude.

14. In an apparatus for timing a balance wheel and hairspring, the combination of, a support adapted to mount a balance wheel for oscillation, means operable when actuated to deliver to a wheel on said support an impulse of gas under pressure, an electrical network operable in response to oscillations of said wheel to generate an electrical impulse each time the wheel stops to reverse its direction of rotation, and means responsive to alternate ones of said electrical impulses and operable to actuate said gas delivery means in timed relation to the alternate electrical impulses to deliver a succession of gas impulses to said wheel in phase with the oscillations of the wheel.
